UNITED STATES PATENT OFFICE.

GUSTAVE M. FAUSER, OF ARDSLEY-ON-HUDSON, NEW YORK.

DESIGN FOR A TEXTILE FABRIC.

Application filed October 13, 1924. Serial No. 11,064. Term of patent 7 years.

To all whom it may concern:

Be it known that I, GUSTAVE M. FAUSER, a citizen of the United States, residing at Ardsley-on-Hudson, Westchester County, State of New York, have invented a new, original, and ornamental Design for Textile Fabrics, of which the following is a specification, reference being had to the accompanying drawing, forming part thereof.

The figure of the drawing is a face view of a piece of textile fabric showing my new design.

The design embodies two birds with long tails at rest combined with stems, flowers, and leaves, all on a plain background.

I claim:

The ornamental design for a textile fabric as shown and described.

GUSTAVE M. FAUSER.
